ROTARY MIXER

John I. Spangler and John A. Eades, York, Pa., and Eugene H. Purdy, Washington, D. C., assignors to Read Machinery Company, Incorporated, York, Pa., a corporation of Pennsylvania

Application May 31, 1938, Serial No. 211,050

14 Claims. (Cl. 259—109)

This invention relates to rotary mixers of the type including an agitator adapted to rotate about a horizontal axis within a mixing chamber in a manner such as to impart a stretching and kneading action to the plastic material contained therein.

An important object of the invention is to provide a rotary mixer of the above character in which the agitator is provided with a plurality of rollers of different sizes equi-distantly spaced from its axis of rotation and designed to successively act upon the plastic material, such as dough, to insure a more efficient and uniform working of the material.

15 A further object of the invention is to provide in a mixer of the above character an agitator comprising a rockably mounted pick-up member for swinging the mass of plastic material from one side of the mixing chamber to the other, and 20 a plurality of rollers of stepped sizes mounted upon the agitator and increasing in diameter in a direction opposite to the normal direction of rotation of the agitator, these rollers being adapted to roll over the material and press it against the 25 sides and bottom of the mixing chamber in a manner such as to insure an active and thorough kneading thereof.

The invention has for another object to provide 30 a rotary mixer of the above character in which the pick-up member and rollers which act upon the dough are arranged so as to engage the material at approximately uniformly timed intervals in order to insure the smooth and balanced operation of the mixer, and to reduce frictional heat, 35 such as might prove deleterious to the finished product.

Still another object of the invention is to provide 40 a mixer of the above character in which the arms of the agitator which support the pick-up member and rollers are so constructed as to act as scrapers during their rotation for clearing away the plastic material which tends to collect adjacent the end walls of the mixing chamber and deflecting it back into the path of the pick-up 45 member and rollers.

A further object of the invention is to provide 50 a mixer of the above character including means whereby the axis of rotation of the agitator may be adjusted to vary the clearance relationship of the rollers and pick-up member to the sides and bottom of the mixing chamber.

Other objects and advantages will be apparent 55 from the following detailed description of a preferred embodiment of the invention, reference being had to the annexed drawings in which:

Figure 1 is a view in vertical transverse cross-section of a dough mixing machine incorporating the novel features of the invention;

Figure 2 is a cross-sectional view of the mixer of Fig. 1 taken on the line 2—2 of that figure; 5

Figure 3 is a cross-sectional view, taken on the line 3—3 of Fig. 2, of one of the arms of the agitator;

Figure 4 is a fragmentary detail view of one of the bearings for the shaft carrying the 10 agitator;

Figure 5 is a view in vertical transverse cross-section of a modified form of mixer;

Figure 6 is a view in vertical transverse cross-section of another modification of a mixer embodying the features of the invention; 15

Figure 7 is a detail view of one of the hubs of the agitator of Fig. 6 taken on the line 7—7 of that figure.

In the drawings is shown a mixer of the open 20 trough type especially suited to the mixing and kneading of dough, although capable of use with other plastic materials. This mixer comprises a deep trough 1 which forms the mixing chamber in which is contained the material to be operated 25 upon and this trough, which is of the dump type, is rockingly supported in a stationary frame 2. Extending longitudinally through the mixing chamber and intersecting its two end walls is a rotatable shaft 3 to which is keyed for unitary 30 rotation therewith an agitator frame—or agitator—4.

The agitator 4 comprises three pairs of arms 5, 6 and 7, the arms of each pair being arranged in parallel and extending radially outward from 35 hubs 8 encircling the shaft 3. The pairs of arms 6 and 7 are of equal length but the pair of arms 5 is of somewhat greater length than those of 6 and 7. Extending between companion pairs of arms are operating members 9, 10 and 11. 40 Member 9 which extends between arms 5 consists of a swing bar having longitudinal offset ends constituting trunnions 9a rotatably journaled within openings provided in the outer ends of the pair of arms 5.

45 Members 10 and 11 comprise hollow rollers of different diameters rotatably supported by the pairs of arms 6 and 7, respectively, at the outer ends of these arms. As best shown by the broken away portion of Fig. 2, each end of a roller is 50 closed by a plug 12 having an extension 12a serving as a trunnion which is loosely received within an opening provided in the outer end of each arm. The openings for receiving the trunnions of the rollers 10 and 11 and the swing bar 9 are each 55

fitted with a bronze bushing 13. The arms 5, 6 and 7 are so spaced angularly about the hubs 8 that the chord distances between the rollers and between the rollers and the swing bar—or, otherwise stated, the distance from center to center of each of the operating members as indicated by the broken line *a* in Fig. 1—are equal. The axes of the rollers thus travel in a common orbital path during rotation of the agitator, while the axis of oscillation of the swing bar revolves outside of such path.

In order to prevent dough from compacting against the end walls of the trough, the arms are shaped, as best indicated in Fig. 3, to function as scrapers. As shown in this figure, which is a cross-section through one of the pair of arms 5 that support the swing bar 9, the arms which travel in close proximity to the end walls of the trough are each arranged at an inclination so as to present a sharpened leading edge 14 and a flat forward face 15 sloping away from an end wall of the trough.

For sealing the openings in the end walls of the trough through which the shaft 3 extends, packing glands 16 including a fibrous packing material 17, are provided, as more clearly shown in Fig. 4. A bronze wear plate 18 seats within a countersink in the outer end of each hub 8 and is held in place by screws 19. This wear plate is adapted to bear against a complementary wear plate 20, which likewise may be of bronze or other non-corrosive metal, closing the inner end of the packing gland. The latter wear plate is likewise received within a countersink on the inner face of the end wall of the trough so as to lie flush therewith and is fastened to the end wall by screws 21.

In the operation of the mixer just described, when motion is imparted to the shaft 3 from any suitable source of power, the agitator 4 is rotated in the direction indicated by the arrow in Fig. 1. This causes the various operating members to be moved through the concave bottom of the trough and into contact with the material contained therein. The operating members thus function initially to thoroughly mix the ingredients constituting the batch.

After the material has attained a dough-like consistency the swing bar 9 in its revolution impacts and embeds within the plastic mass, and in its continued forward and upward movement swings the mass of dough which clings to the swing bar from one side of the mixing chamber to the other where it is forcibly slapped against the rear wall of the trough. Subsequently the roller 10 following the swing bar rolls over the dough and imparts an initial compression thereto so as to flatten it against the rear side and bottom of the trough; then the larger roller 11 trailing the roller 10 passes over the dough to compress it still further.

Since rolling increases the density of the dough mass, and hence the trailing roller 11 encounters greater resistance than the leading roller 10, it is necessary, in order for the mixer to perform most efficaciously, that the roller 11 should be larger than the roller 10 so as to overcome this resistance and impart additional compression to the dough. Such size relationship between the rollers 70 also avoids dragging of the rollers over or through the mass of dough, which rapidly develops frictional heat. By adopting rollers of suitably large and different sized diameters and mounting them equidistantly from the axis of rotation of the agitator, a minimum amount of power is required

to rotate the agitator for the reason that there is less tendency for the material to pile up in front of and crowd over the tops of the rollers.

While the exact sizes of the rollers to be adopted will depend essentially upon the character and capacity of the mixer, a relationship which has been found to be satisfactory for the usual standard size commercial mixing machines is that in which the rollers 10 and 11 are 2 inches and 5 inches in diameter, respectively, and so located with relation to the mixing chamber as to afford a clearance of 5 inches and 3½ inches, respectively, with the bottom of the trough.

Since the swing bar is free to oscillate upon its trunnions, it yields slightly upon impact with the dough and the latter is relieved from the full force of the blows delivered by the swing bar in its revolution; and because the swing bar and rollers are equidistantly spaced apart about the agitator the various operating members act at substantially uniformly timed intervals. Both of these factors conduce to a smoother and more vibrationless operation of the mixer and to the avoidance of overheating of the dough.

During rotation of the agitator the sharpened leading edges of the pairs of arms 5, 6 and 7 cut through the mass of dough adjacent the end walls of the trough and turn this dough back toward the center of the mixing chamber.

In Fig. 5 is shown a modified form of dough mixer. This mixer corresponds generally to the mixer of Figs. 1 through 4 just described and comprises a trough 30 constituting a mixing chamber through which extends in a longitudinal direction a shaft 31 carrying an agitator 32. This agitator, like the agitator 4 of the mixer above described, is provided at each end with arms 33, 34, 35 and 36 extending radially from a hub 37, and supported by companion pairs of arms are rollers 38, 39, 40 and 41. As indicated in the drawings, the roller 38 is of solid cross-section while the remaining rollers are hollow and of comparatively light construction.

The arms are of equal length except the pair of arms 33 which are of somewhat greater length than the arms 34, 35 and 36. The roller 38 rotatably journaled in the ends of the pair of arms 33 is of comparatively small diameter and during the operation of the mixer is designed to function as the pick-up member, corresponding to the swing bar 9 of the mixer of Figs. 1 through 4.

The rollers 39, 40 and 41 are of stepped sizes, increasing in diameter contra to the direction of rotation (indicated by the arrow) of the agitator. These rollers may be rotatably journaled in the outer ends of their arms in the same manner as the rollers 10 and 11 of the mixer first described. In the case of the usual standard size commercial mixers the rollers 38, 39, 40 and 41 may be of 2-inch, 3-inch, 4-inch and 5-inch diameters, respectively, and the position of the agitator with relation to the mixing chamber such that these rollers afford a clearance with the bottom of the trough of 2 inches, 5 inches, 4½ inches and 4 inches, respectively.

The arms 33 and 35 extend in alignment from diametrically opposite points upon the hub 37. In order, however, that the chord distances between the centers of the rollers 38, 39, 40 and 41 be equal the arms 34 and 36 are disposed at an angle of more or less than 90 degrees with reference to their adjacent arms, as shown in Fig. 5. As also indicated by this figure the arms are formed with sharpened leading edges 42 so

as to cut through the dough adjacent the end walls of the trough and turn it back toward the middle of the mixing chamber.

The dough mixer of Fig. 5 functions substantially the same as the mixer previously described. As the agitator rotates in the direction indicated by the arrow in this figure, the small size pick-up roller 38 acts to engage and slap the batch of dough against the rear side of the mixing trough after which the rollers 39, 40 and 41 come successively into play to press the dough against the sides and bottom of the trough to effect a thorough mixing and kneading of the same.

Instead of using a small size roller, such as the roller 38, for the pick-up member, a swing bar corresponding to the swing bar 9 of the mixer of Figs. 1 through 4 may be employed. And, alternatively, a small roller may be substituted for the swing bar 9 of the mixer of Figs. 1 through 4 if found desirable. Where, however, a roller serves as the pick-up bar it should be of comparatively small diameter—in the neighborhood of 2 inches—in order to properly perform its function. A roller or swing bar of small diameter has been found superior to a fixed bar, such as has been usually employed in the past as the pick-up member, for the reason that the roller or swing bar being free to turn on its trunnions is enabled to swing the mass of dough from one side of the mixing chamber to its other without the same tendency to tear loose from the dough as is the case with a rigidly mounted pick-up bar.

Illustrated in Fig. 6 in transverse cross-section is a mixer corresponding to the mixer of Figs. 1 through 4 insofar as comprising a trough 50 of the open-top type forming a mixing chamber, a rotatable shaft 51 extending longitudinally through the trough, and an agitator 52 carried by the shaft and located within the mixing chamber. The agitator 52, like the agitator 4 of the first-described mixer, comprises at each end radial arms 53, 54 and 55 extending outward from a hub 56 encircling and keyed to the shaft 51. These arms and hubs are duplicated at opposite ends of the agitator adjacent the end walls of the mixing chamber and the arms are formed to act as scrapers in a manner which has already been explained in connection with the two before-described mixers of Figs. 1 through 5.

The pairs of arms 54 and 55 are of equal length and rotatably support rollers 57 and 58, respectively. The trailing roller 58 mounted in the ends of the pair of arms 55 is of somewhat larger diameter than the leading roller 57 supported in the ends of the pair of arms 54. The arms 53 are longer than the arms 54 and 55, and mounted for oscillation in the ends of this longer pair of arms is a longitudinally-offset swing bar 59, corresponding to the swing bar 9 of the mixer illustrated in Fig. 2. The chord distances between the various operating members—i. e., the center to center distances between the two rollers and between the rollers and the swing bar—are equal. As thus far described the mixer corresponds in all major respects to the mixer illustrated in Figs. 1 through 4; and if desired the swing bar 59 may be replaced by a small size pick-up roller, as described in connection with the mixer of Fig. 5.

As shown in Fig. 7, the series of arms 53, 54 and 55 at each end of the agitator are not formed integral with the hub 56 but instead extend out from a collar 60 which snugly encircles the hub. The hub is fashioned with an an-

nular seat 61 adapted to receive an inwardly directed flange 62 surrounding the opening in the collar. The collar is held in rigid association with the hub by means of a series of bolts 63 which pass through equidistantly spaced holes in the flange and engage threaded openings in the hub.

By virtue of this construction, the clearance of the rollers and swing bar with the bottom and sides of the trough may be readily adjusted by removing the bolts 63, angularly shifting the collars 60 at opposite ends of the agitator about their eccentric hubs 56 until different threaded bolt holes come into registry with the bolt holes in the hubs and then replacing the bolts to fasten the arms in their new positions of adjustment. Since rotation is imparted to the arms from the shaft 51, adjustment of the collars about their hubs causes a bodily displacement of all the arms relative to the axis of the shaft so as to simultaneously change the positions of the swing bar and rollers relative to the trough. The opposite limit of adjustment of the arms from that shown in full lines in Fig. 6 is indicated in broken lines in the same figure.

The operation of the mixer just described is substantially the same as that of the mixers of Figs. 1 through 5, heretofore described. Any suitable number of rollers of stepped sizes may be adopted in conjunction with this modification, the two rollers shown in Fig. 6 being suggestive only.

The invention may be embodied in other specific forms without departing from the spirit or essential characteristics of the invention, and the present embodiment is therefore to be considered as illustrative and not restrictive, and all changes which come within the meaning and range of equivalency of the claims are therefore intended to be embraced therein.

We claim:

1. A dough mixer comprising a mixing chamber and an agitator within said mixing chamber arranged for rotation about a horizontal axis, said agitator comprising a plurality of freely rotatable rollers all of different diameters supported at equal distances from the axis of rotation of the agitator and a freely rotatable pick-up member supported at a greater distance from said axis of rotation.

2. A dough mixer comprising a mixing chamber and an agitator within said mixing chamber arranged for rotation about a horizontal axis, said agitator comprising a plurality of freely rotatable rollers of different diameters supported at equal distances from the axis of rotation of the agitator, said rollers increasing in size in a direction opposite to the normal direction of rotation of the agitator and adapted to successively act upon material contained in the mixing chamber and a freely rotatable pick-up member supported at a greater distance from said axis of rotation and intermediate the rollers of smallest and largest diameters.

3. A dough mixer comprising a mixing chamber and an agitator within said mixing chamber arranged for rotation about a horizontal axis, said agitator comprising a plurality of freely rotatable rollers of different diameters supported at equal distances from the axis of rotation of the agitator, said rollers increasing in size in a direction opposite to the normal direction of rotation of the agitator and adapted to successively act upon material contained in the mixing chamber and a freely rotatable pick-up member

- supported at a greater distance from said axis of rotation and intermediate the rollers of smallest and largest diameters, the chord distance between adjacent rollers and between the pick-up member and its adjacent rollers being equal.
4. A dough mixer comprising a mixing chamber and an agitator within said mixing chamber arranged for rotation about a horizontal axis, said agitator comprising a plurality of freely 10 rotatable rollers of different diameters supported at equal distances from the axis of rotation of the agitator, said rollers increasing in size in a direction opposite to the normal direction of rotation of the agitator and adapted to successively act upon material contained in the mixing chamber and a freely rotatable longitudinally offset swing bar supported at a greater distance from said axis of rotation and intermediate the rollers of smallest and largest diameters.
- 20 5. A dough mixer comprising a mixing chamber and an agitator within said mixing chamber arranged for rotation about a horizontal axis, said agitator comprising a plurality of pairs of arms of equal length and a pair of arms of greater length, freely rotatable rollers all of different sizes mounted within and extending between the companion arms of equal length and a freely rotatable pick-up member mounted within and extending between the arms of greater length.
- 30 6. A dough mixer comprising a mixing chamber and an agitator within said mixing chamber arranged for rotation about a horizontal axis, said agitator comprising a plurality of pairs of arms of equal length and a pair of arms of greater length, freely rotatable rollers all of different sizes mounted within and extending between the companion arms of equal length and a longitudinally offset swing bar rotatably mounted in and extending between the arms of greater length.
- 40 7. A dough mixer comprising a mixing chamber and an agitator within said mixing chamber arranged for rotation about a horizontal axis, said agitator comprising a plurality of pairs of arms of equal length and a pair of arms of greater length, freely rotatable rollers all of different sizes mounted within and extending between the companion arms of equal length and a freely rotatable pick-up roller of small diameter mounted within and extending between the arms of greater length.
- 45 8. A dough mixer comprising a mixing chamber and an agitator within said mixing chamber arranged for rotation about a horizontal axis, said agitator comprising a plurality of pairs of arms of equal length and a pair of arms of greater length, freely rotatable rollers all of increasing size mounted within and extending between the companion arms of equal length adapted to successively act upon material contained in the mixing chamber and a freely rotatable pick-up member extending between the arms of greater length and located intermediate the rollers of smallest and greatest diameter.
- 55 9. A dough mixer comprising a mixing chamber and an agitator within said mixing chamber arranged for rotation about a horizontal axis, said agitator comprising a plurality of pairs of arms of equal length and a pair of arms of greater length, freely rotatable rollers of different size mounted within and extending between the companion arms of equal length adapted to successively act upon material contained in the mixing chamber and a freely rotatable longitudinally offset swing bar extending between the arms of greater length and located intermediate the rollers of smallest and greatest diameter.
10. A dough mixer comprising a mixing chamber and an agitator within said mixing chamber arranged for rotation about a horizontal axis, said agitator comprising a plurality of pairs of arms of equal length, and a pair of arms of greater length, freely rotatable rollers all of different sizes mounted within and extending between the companion arms of equal length, a freely rotatable pick-up member extending between the arms of greater length, hubs eccentrically disposed relative to the axis of rotation of the agitator, collars surrounding the hubs and united with the inner ends of the arms at opposite ends of the agitator and detachable means connecting said collars to the hubs but permitting angular adjustment of the collars relative thereto.
- 20 11. The combination with a mixer of the type comprising a mixing chamber, an agitator within said mixing chamber having a plurality of longitudinally-extending operating elements and shafts supporting said agitator at its ends for rotation within said mixing chamber, of means for varying the clearance between the operating elements and the wall of the mixing chamber, said means comprising hubs eccentrically mounted on the shafts adjacent the ends of the agitator for rotation with said shafts and supporting means for the operating elements detachably connected to the hubs and adjustable angularly to different positions thereabout.
- 25 12. The combination with a mixer of the type comprising a mixing chamber, an agitator within said mixing chamber having a plurality of longitudinally-extending operating elements and shafts supporting said agitator at its ends for rotation within said mixing chamber, of means for varying the clearance between the operating elements and the wall of the mixing chamber, said means comprising cylindrical hubs eccentrically mounted on the shafts adjacent the ends of the agitator for rotation with said shafts, collars encircling said hubs, arms extending outward from said collars and supporting the operating elements and means detachably connecting the collars to the hubs to permit rotation of the collars about the hubs to different positions of adjustment.
- 30 13. The combination with a mixer of the type comprising a mixing chamber, an agitator within said mixing chamber having a plurality of longitudinally-extending operating elements and shafts supporting said agitator at its ends for rotation within said mixing chamber, of means for varying the clearance between the operating elements and the wall of the mixing chamber, said means comprising cylindrical hubs eccentrically mounted on the shafts for rotation therewith, collars surrounding said hubs, arms extending outward from said collars and arranged in pairs at opposite ends of the agitator for supporting the operating elements therebetween, a plurality of pairs of said arms being of substantially equal length.
- 35 14. The combination with a mixer of the type comprising a mixing chamber, an agitator rotatable within said mixing chamber including a plurality of longitudinally-extending rollers of stepped sizes and all increasing in size in a direction opposite to the normal direction of rotation of the agitator, and shafts supporting said agitator at its ends for rotation, of means for

varying the clearance between the rollers and the wall of the mixing chamber, said means comprising cylindrical hubs eccentrically mounted on the shafts adjacent the ends of the agitator for rotation with said shafts, collars encircling said hubs, arms of substantially equal length

extending outward from said collars and arranged in pairs at opposite ends of the agitator for supporting the rollers therebetween.
